UNITED STATES PATENT OFFICE.

SAMUEL R. HARDY AND ROYAL A. COCHRAN, OF DAYTON, TEXAS.

AUTOMATIC BRAKE-SETTING DEVICE.

Application filed July 12, 1921. Serial No. 484,137.

To all whom it may concern:

Be it known that we, SAMUEL R. HARDY and ROYAL A. COCHRAN, citizens of the United States, residing at Dayton, in the county of Liberty and State of Texas, have invented certain new and useful Improvements in an Automatic Brake-Setting Device, of which the following is a specification.

10 This invention relates to new and useful improvements in an automatic brake setting device.

One object of the invention is to provide an apparatus which is connected to a railway block signal, and operated thereby, to automatically release the air, and set the brakes of the train, in case the signal is ignored, and thereby stop the train.

Another object is to provide a device of this character which may be readily connected to the signals now in common use and which will not require any change in the construction of the locomotive and car equipment now in common use.

25 A further feature resides in the provision of a simple and inexpensive apparatus which will be positive and accurate in operation.

With the above and other objects in view this invention has particular relation to certain novel features of construction, operation and arrangement of parts, an example of which is given in this specification and illustrated in the accompanying drawings, wherein:—

35 Figure 1 is a side view of the device partially in section, and

Figure 2, shows a front elevation, partially in section.

Referring to the drawings, the numeral 1 40 designates a railway track and 2 designates the truck which moves thereon. At one side of the track there is a box 3 in which is enclosed a wedge like plunger 4. This plunger moves on roller bearings as 5 enclosed in the bottom of the box.

The numeral 6 designates the signal stand which carries the signal 7. Fastened to, and operated by the signal, there is a sprocket wheel 8 in alignment with a corresponding 50 wheel 9 rotatably mounted on the stand

beneath the signal. A sprocket chain 10 operates over these wheels and operates the latter from the former. The sprocket wheel 9 is connected to the plunger 4 through the connecting rod 11.

Pivoted at one end in the box 3, there is a blade 12 which works through a slot 13 in the top of the box. When the signal is set to permit the train to proceed the plunger 4 is withdrawn from under said blade, through the mechanism described, but when the signal is set to stop the train the plunger 4 is driven forwardly, through the rod 11, and runs under and lifts the blade and projects it up through the slot 13, some distance 65 above the level of the rails.

A hanger 14 is provided which is attached to the front journal box of the truck and depending from it are the rods 15, 15, whose lower ends sustain a vertically moveable cross head 16.

The lower ends of the rods 15 support a frangible plug 17, which plugs air line 18, leading from the main hose. The cross head is hood-like in form and partially surrounds and protects the plug 17, as illustrated in Figure 1. Should the engineer refuse to stop when the signal is set against him the blade 12, being in elevated position, will break the plug 17 and release the air 80 with the result that the brakes will be automatically set and the train stopped.

Any other device for releasing the air from the line 18 may be substituted for the plug 17, if desired.

What we claim is:—

In combination a box arranged alongside a railway track, a wedge shaped plunger movable transversely through said box, a signal stand, a movable signal mounted thereon, operative connections between the signal and plunger through which the latter may be actuated from the former, the top of said box being provided with a slot, a blade in said box pivoted at one end and aligned with 90 and adapted to work through said slot, said plunger being disposed to work underneath said blade and to move the same upwardly when in one position but to permit the same to be lowered by gravity when in another 100

position, a hanger attached to a railway truck, a frangible plug in the air line of the train and supported by said hanger and arranged in position to align above said blade 5 a vertically movable cross head partially surrounding said plug.

In testimony whereof we have signed our

names to this specification in the presence of two subscribing witnesses.

SAMUEL R. HARDY.
ROYAL A. COCHRAN.
